UNITED STATES PATENT OFFICE.

EDWIN M. ROSENBLUTH, OF PHILADELPHIA, PENNSYLVANIA.

AUTOMOBILE RADIATOR WATER HEATER.

Application filed October 7, 1916. Serial No. 124,211.

To all whom it may concern:

Be it known that I, EDWIN M. ROSENBLUTH, a citizen of the United States, residing at Philadelphia, in the State of Pennsylvania, have invented a certain new and useful Improvement in Automobile Radiator Water Heaters, whereof the following is a specification, reference being had to the accompanying drawing.

- 10 The primary object of my invention is to provide means to heat the water in the circulating system of an internal combustion engine on an automobile, including a radiator, by a source of heat independent of said engine and for the purpose of preventing the water from freezing in said system when the engine is not being operated; the water in said system being, of course, heated by said engine, when the latter is operated.
- 15 As hereinafter described, my invention includes a blue flame oil burning heater which is separable from and portable independently of and such circulating system above contemplated; so that it may be shifted from place to place in a garage, for temporary connection with different automobiles to heat the water in the respective circulating systems thereof, by a hot blast including atmospheric air and products of combustion from said heater, directed through the interstices of the radiators which are included in such systems. As the radiators are presented at respectively different heights on the automobiles which carry them, and it is desirable to have the products of combustion from the heater delivered to the radiators at the lower portion thereof, because that is the region where the heat may be most efficiently applied; an essential feature of the invention herein claimed is means for conducting or directing the products of combustion from the heater to the radiator, so constructed and arranged that the discharge end of the conducting or directing means is adjustably variable in position with reference to the radiator; so that a single heater, having such adjustable conducting or directing means, is thereby adapted for the most efficient cooperation with automobile radiators of any kind, despite variations in the height at which such radiators are carried

by the automobiles. Moreover, as such radiators are variously plane and angular at their fronts with which such conducting or directing means of my improved heaters 55 are intended to cooperate; a convenient adjunctive feature of my invention is the provision of means at the discharge end of the conduit for the products of combustion whereby it is adjustable in conformity with 60 the front of a radiator, whether such front be plane or angular.

My invention includes the various novel features of construction and arrangement hereinafter more definitely specified. 65

In the drawing; Fig. I is a side elevation of a radiator in the elevated position, in which it is carried by an automobile, and having a heater embodying my invention in cooperative relation therewith. The dash 70 lines in said figure indicate several different positions of the hot blast conducting or directing means whereby the region of discharge of said blast from the heater may be variably adjustably determined. 75

Fig. II is a front elevation of the radiator and heater shown in Fig. I.

Fig. III is a sectional view taken on the line III, III in Fig. I.

Fig. IV is a fragmentary sectional view 80 showing the construction of the telescopic joint of the hot blast conduit shown in Figs. I and III.

Fig. V is a plan view of a radiator having an angular front, and showing a hot blast 85 conduit having means adjusted to fit said angular front, and adjustable to fit radiator fronts of different angles or which are plane.

Referring to the form of my invention shown in Figs. I to IV inclusive; the automobile radiator 1 has the water inlet pipe 2 at the bottom thereof and the water outlet pipe 3 at the top thereof connecting it with the water circulating system of an internal combustion engine 4, which is the motor of 90 the automobile. The heater, which is separable from said radiator and portable to other radiators, conveniently includes the casing 5 having the door 6, with the foraminous screen 7, affording access to its interior. Said casing incloses a flaming source 100 of heat having an air inlet and air outlet

provided with foraminous screens such as to prevent ignition of an explosive atmosphere therethrough. For instance, such a source may include the hydrocarbon burner 9 having the controlling handle 10 whereby the height of the flame 11 may be regulated; said burner being conveniently inclosed in the lamp casing 12 having the foraminous door 13 affording an air inlet to said burner, 10 and having the foraminous chimney 15 affording an outlet from said burner; both inlet and outlet being of such a foraminous nature that it is impossible for an explosive atmosphere to find access to said flaming 15 source of heat and, consequently, said heater may be operated with safety in an atmosphere charged with gasoline fumes.

Said casing 5 has means to direct and conduct the hot blast of products of combustion from said heater mixed with atmospheric air, including the removable annular cap 16 which is detachably secured on said casing 5 by the screws 17; the conduit section 18 which is vertically and circumferentially adjustable in said cap; and the conduit section 19 which is horizontally and circumferentially adjustable in said conduit section 18. It is to be understood that the telescopic relation of said casing cap 16 to 20 the conduit section 18, and of said conduit section 18 to said conduit section 19, is such that the discharge end 20 of said conduit may be presented at any desired height and vertical distance from the center of said 25 heater casing 5 required to place it in the most efficient position with respect to any given radiator.

As shown in Figs. III and IV; the cylindrical portion of said conduit section 19 is longitudinally adjustable in the horizontally cylindrical portion of said conduit section 18 which is provided with the sphincteral band 22 which is retained between the circumferential beads 23 on said 30 section 18 and has its ends provided with the clamping bolt 25 and nut 26 by which said band may be constricted upon said conduit section 18 to constrict the latter upon said conduit section 19; the end of said section 18 being conveniently slotted as indicated at 27 in Fig. III to permit such constriction.

It is to be understood that said casing cap 16 is provided with the sphincteral band 29 which is retained between the beads 30 on said cap and otherwise constructed and arranged to be constricted like said band 22.

As shown in Figs. I and II the discharge end section 19 of the hot blast conduit has 60 its discharge end 20 planular to fit the plane front face of said radiator 1. However, the discharge end conduit section 32, shown in Fig. V, although having a plane discharge end 33, is adapted to fit a radiator 65 34 having an angular front 35, by means of

the adjustable hood comprising the oppositely counterpart conforming sections 37 which are pivoted upon a vertical clamping bolt 38 having the adjustable wing nut 39 so that they may be swung toward and 70 away from the radiator and thus adapted to the configuration of the latter, and be then clamped in adjusted position. It is to be understood that such a discharge end section of the conduit may be telescopically fitted in the section 18 aforesaid; thus providing the heater above described with means adapting it for cooperation with radiators which are either plane or angular at their 75 fronts.

As far as I am aware, I am the first inventor of a heater for an automobile water circulating system which is separable from and portable independently of said system, with the advantage that a single heater may 80 be successively connected in cooperative relation with a plurality of such systems, and, so far as I am aware, I am the first inventor of a water heater of any kind having 85 a flaming source of heat, and provided with 90 foraminous screens to exclude an explosive atmosphere.

Therefore, I do not desire to limit myself to the specific construction and arrangement herein set forth, as it is obvious that 95 various modifications may be made therein without departing from the essential features of my invention as defined in the appended claims.

I claim:—

1. The combination with a flaming source of heat having an air inlet and an air outlet; of foraminous screens for said inlet and outlet adapted to prevent ignition of an explosive atmosphere therethrough; a casing 105 for said source arranged to direct the hot blast therefrom; means arranged to direct and conduct said hot blast in cooperative relation with an automobile radiator, including a conduit having its discharge end 110 adjustable both vertically and horizontally with respect to said casing; conforming means, at said discharge end, including an adjustable hood comprising pivotally connected, oppositely counterpart sections movable to fit the adjacent face of said radiator; clamping means securing said conforming means in adjusted position; and means constructed and arranged to secure 115 said conduit in adjusted position. 120

2. The combination with a flaming source of heat having an air inlet and an air outlet; of foraminous screens for said inlet and outlet adapted to prevent ignition of an explosive atmosphere therethrough; a casing 125 for said source arranged to direct the hot blast therefrom; means arranged to direct and conduct said hot blast in cooperative relation with an automobile radiator, including a conduit having its discharge end 130

adjustable both vertically and horizontally with respect to said casing; conforming means, at said discharge end, including a bifurcated hood, movable to fit the adjacent 5 face of said radiator; and means constructed and arranged to secure said conduit in adjusted position.

In testimony whereof, I have hereunto signed my name at Philadelphia, Pennsylvania, this sixth day of October, 1916.

EDWIN M. ROSENBLUTH.
